United States Patent Office

Des. 204,888
Patented May 24, 1966

204,888

INSIGNIA

Stafford F. Potter, Arlington, Va., assignor to United States of America as represented by the Secretary of the Army

Filed Sept. 3, 1963, Ser. No. 76,462

Term of patent 14 years

(Cl. D29—2)

FIG. 1

FIG. 2

FIG. 1 is a front elevation of an insignia showing my new design.

FIG. 2 is a side elevation thereof.

It is understood that the design may be embodied in such articles as a medallion, badge, plaque, sign, officer insignia or enlisted insignia without departing from the spirit of the invention.

The rear of my new design for an insignia is plain and unornamented.

The design described herein may be reproduced and used by or for the Government for governmental purposes without the payment to me of any royalty thereon.

I claim:

The ornamental design for an insignia, as shown and described.
